(57) **CLAIM**

The ornamental design for a mobile energy storage power-supply unit as shown and described.

DESCRIPTION

FIG. 1 is a front, left and bottom perspective view of a mobile energy storage powersupply unit, showing my new design.

FIG. 2 is a rear, right and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 1.

FIG. 11 is an enlarged view of detail 11 in FIG. 2.

FIG. 12 is an enlarged view of detail 12 in FIG. 2; and,
 FIG. 13 is another front, left and top perspective view of the
 mobile energy storage powersupply unit of FIG. 1 shown in
 another configuration of use.

The dashed broken lines depict portions of the mobile
 energy storage powersupply unit that form no part of the
 claimed design. The dot-dash broken lines in FIGS. 1, 2, and
 9-12 depict the boundaries of the enlarged views and form
 no part of the claimed design.
